FOREIGN PATENT DOCUMENTS

CA 2976560 A1 2/2019

Primary Examiner — Ryan Harvey(74) *Attorney, Agent, or Firm* — Rockridge Venture Law; Kevin Christopher; Andrew Lerner(57) **CLAIM**

The ornamental design for an extension and flexion mobility device, as shown and described.

DESCRIPTION

FIG. 1 is a left-side front perspective view of my mobility device in its flexion configuration;

FIG. 2 is a left-side rear perspective view thereof;

FIG. 3 is a left side elevational view thereof;

FIG. 4 is a front elevational view thereof;

FIG. 5 is a top plan view thereof;

FIG. 6 is a rear perspective view of my mobility device in its extension configuration;

FIG. 7 is front perspective view thereof;

FIG. 8 is a right-side elevational view thereof;

FIG. 9 is a rear elevational view thereof; and,

FIG. 10 is a top plan view thereof.

1 Claim, 10 Drawing Sheets---
